CLAIM

The ornamental design for a building controller as shown and described.

DESCRIPTION

FIG. 1 is a perspective view of a building controller; FIG. 2 is a front side view of the building controller of FIG. 1;

FIG. 3 is a left side view of the building controller of FIG. 1;

FIG. 4 is a right side view of the building controller of FIG. 1;

FIG. 5 is a top plan view of the building controller of FIG. 1; and,

FIG. 6 is a bottom plan view of the building controller of FIG. 1.

The portions illustrated in broken lines on the figures are for illustrative purposes only and form no part of the claimed design.

1 Claim, 6 Drawing Sheets
